METHOD OF FORMING WING NUTS FROM SHEET METAL

George Pavlinetz, Carteret, N. J.

Application August 28, 1951, Serial No. 244,063

7 Claims. (Cl. 10—86)

This invention relates to winged fasteners produced from sheet metal stock and the method of producing them.

Whereas the production of winged fasteners from sheet metal has been proposed over many years, none of the products of this type has possessed adequate strength to resist deformation forces to which they are commonly subjected, rendering it necessary to turn to the more expensive cast and forged varieties wherever any degree of strength is required.

It is among the objects of this invention to produce relatively simple, strong winged fasteners from sheet metal requiring no castings or forgings and avoiding drilling and welding operations as well as the use of expensive dies.

The method of making winged fasteners from sheet metal stock contemplated herein comprises forming a flat blank into a body having a tubular thread-carrying portion and a flaring wing-forming portion diverging therefrom, pressing opposed wall surfaces of the wing-forming portion into contact to produce wings, and providing a screw thread for the thread-carrying portion. The sheet metal stock from which the fasteners are formed is preferably pressed or drawn to form a central tubular portion, following which the blank is stamped from the stock and opposed notches may be formed in its periphery. The portion extending from the tubular part thus formed is then flared, and by means of suitable dies, pressed substantially normally to the center line of the notches to form the wings and a terminal flange is produced in radially disposed relationship at the other end of the tubular portion of the body.

One end of the tubular body may be closed, which may be effected by continuing the wing formation across one end of the body. Spaced thread-carrying portions may be provided by the tubular body and internal threads may be formed in the body by radially pressing the tubular portion thereof. Where the winged fastener is to assume the form of a bolt, the pressing operation will define a stop to limit the position of the bolt and will secure the end of the bolt in the body against relative rotation. This securing effect may be produced simultaneously with the formation of the wings.

The sheet metal winged threaded fastener contemplated herein comprises a tubular body having opposed radial double-walled wings integral therewith, and a radial reinforcing flange formed at the other end of the body. The wings preferably project beyond one end of the tubular body and likewise extend for a substantial distance along its length. The tubular body may be closed at one end and in certain instances, the wing structure itself serves to produce the closure. The tubular body may be internally threaded and its radial flange may be inwardly directed and likewise internally threaded. The radial flange may assume a reentrant form so that spaced threads may be provided to produce a locking action with respect to a member upon which such a winged nut is threaded.

A more complete understanding of the invention and

2

its objects will follow from a detailed description of the accompanying drawings wherein:

Fig. 1 is an elevation of a winged nut embodying the present invention;

Fig. 2 is an end elevation of the nut shown in Fig. 1;

Fig. 3 is a plan view of the same nut;

Fig. 4 is a section taken along line 4—4 of Fig. 1;

Fig. 5 is a plan view of a partially formed blank from which the nut of Fig. 1 is produced;

Fig. 6 is an elevation of the right end of Fig. 5;

Fig. 7 is a front elevation of the blank of Fig. 5 after it has received a further forming operation;

Fig. 8 is an elevation partially in section depicting the operation of the dies during an intermediate step of the formation of the nut of Fig. 1;

Fig. 9 is an elevation partially in section depicting the operation of another pair of dies in the formation of the nut of Fig. 1;

Fig. 10 depicts a modified form of winged nut in elevation;

Fig. 11 is an end elevation of the nut of Fig. 10;

Fig. 12 is a plan view of the nut of Fig. 10;

Fig. 13 is a section taken along line 13—13 of Fig. 10;

Fig. 14 is an elevation of a partially formed blank employed in the production of the nut of Fig. 10;

Fig. 15 is a bottom plan view of the blank of Fig. 14;

Fig. 16 is an elevation of the blank of Fig. 14 after it has been subjected to a further forming operation;

Fig. 17 is an elevation partially in section of the same blank after it has been subjected to a subsequent operation;

Fig. 18 is an elevation partially in section depicting the operation of the dies in forming the partially completed blank of Fig. 17;

Fig. 19 depicts in a partially sectional elevation the operation of dies in a subsequent forming operation on the nut of Fig. 10;

Fig. 20 is an elevation of a modified form of winged nut;

Fig. 21 is an end elevation of the nut of Fig. 20;

Fig. 22 is an elevation of a winged bolt embodying certain aspects of the present invention;

Fig. 23 is a sectional elevation depicting an intermediate step in the production of the winged bolt of Fig. 22;

Fig. 24 is an elevation, partially in section, depicting the operation of the dies in producing the winged bolt of Fig. 22;

Fig. 25 is an elevation of a modified form of winged bolt;

Fig. 26 is a sectional elevation of an intermediate product produced in the formation of the winged bolt of Fig. 25; and

Fig. 27 is an elevation partially in section of the operation of the dies in producing the winged bolt of Fig. 25.

The blank 30 depicted in Fig. 5 is shown as containing a central opening 32 extending through a tubular sleeve 34 preferably formed by pressing or drawing prior to the removal of the blank 30 from the stock, not shown.

The blank 30 is also provided with opposed notches 36 symmetrically disposed with respect to a diameter of the blank. After the blank has thus been formed with its sleeve 34 and notches 36, it is subjected to a pressing operation to produce a flaring wall 38 of frusto-conical shape, diverging outwardly from the sleeve 34. The partially completed article of Fig. 7 receives an internal die 40, shown in Fig. 8, and is in turn received between external dies 42 and 44 which collapse the flared wall 38 to define the double-walled wings 46 extending radially from a tubular portion 48 formed as a continuation of the sleeve 34.

A subsequent operation is performed, as depicted in Fig. 9 wherein an internal die 50 cooperates with external dies 52 and 54 to produce an out-turned radial flange 56 at the lower end of the tubular portion of the product, a lip 58 carried by the die 54 cooperating with an edge 60 of the die 52 to shear the upper edges of the wings to their desired shape. The opposed portions of the dies 52 and 54 bearing upon the wings 46 may be roughened to define indented surfaces 62 on the wings, and the internal die 50 may be threaded so that the internal threads 64 depicted in Fig. 4 will be formed simultaneously with the pressing operation, internally of the tubular portion 48.

It will be noted that the wings extend for a substantial distance longitudinally along the tubular portion 48 and project appreciably thereabove providing readily engageable portions for application and removal of the nut with respect to a threaded member. The radial flange 56 provides appreciable strength at one end of the tubular member resisting deformation forces that would tend to collapse the nut and shorten its life, the double-walled wings providing a substantial degree of strength at the other end of the product to resist undesired deformation.

In producing the modified form of winged nut depicted in Fig. 10, a blank is pressed or drawn to the form depicted in Fig. 14 having a lower tubular portion 70 closed by a bottom wall 72, the upper edge intersecting a substantially spherical wall 74 diverging or flaring towards an open end 76 containing opposed notches 78. By means of suitable dies, the lower tubular portion 70 is upset to produce a configuration similar to that depicted in Fig. 16 wherein an outwardly directed flange 80 and an inwardly directed flange 82 define what may be termed a reentrant flange, better shown in Fig. 17. The semi-finished article of Fig. 16 is subjected to a further pressing operation which penetrates the lower wall 72 to form an opening 84 defined by a short tubular wall 86 pressed upwardly from the inturned flange 82. The formation of this structure between internal dies 88 and 90 and external dies 92 and 94 has been depicted in Fig. 18. Following this operation, an internal die 96 is inserted in the partially completed product and the entire assembly subjected to the action of external dies 98 and 100 as shown in Fig. 19, it being understood that the internal die 96 may be provided with external threads so as to form the internal threads 102 and 104 internally of the tubular portions 106 and 86 of the product respectively, as shown in Fig. 13. The pressing operation as depicted in Fig. 19 collapses the upper flaring portion 74 of the body about the internal die 96 to form the upper tubular portion 106 and the double-walled wings 108. The article produced as shown in Fig. 19 may be subjected to subsequent operations to trim excessive material or perform other functions, similar to the arrangement depicted in Fig. 9 with respect to the preceding form of the invention.

As depicted in Fig. 18, the upper internal die may be provided with a bore 110 to receive the lower internal die 88 together with such material as will be punched from the lower wall 72 when the lower internal die is forced upwardly into the upper one.

A modified form of winged nut is depicted in Figs. 20 and 21 wherein the upper end of the tubular portion 112 is closed by a wall 114 during the pressing operation. The reference characters of the modification shown in Fig. 1 of the drawings have been used as far as applicable to these figures as well. The method of producing this structure is somewhat similar to that employed in producing the structure of Fig. 1, the dies in the case of the form shown in Figs. 20 and 21 being designed to provide a closed upper end for the tubular internally threaded portion 112. The material of the winged nut between its upper edge and the broken line 116 will be trimmed between suitable dies to produce the configuration shown in Fig. 20 by full lines.

The winged bolt depicted in Fig. 22 is produced quite similarly to the nuts of Figs. 1 and 20. In this case, a bolt 118 has an upper end provided with serrations 120 to assure frictional engagement with the body of the winged fastener so that there will be no relative rotation. The lower end of the bolt 118 is provided with threads 122 projecting below the outwardly directed radial flange 56 of the body. The outwardly flared frusto-conical portion 38 as depicted in Fig. 23 is collapsed about the 10 serrated upper end of the bolt 118 by means of suitable dies as depicted in Fig. 24, comprising a table 124, a fixture 126 receiving the threaded end of the bolt, and external dies 128 and 130 which force the wall of the tubular portion 112 into binding relationship with the serrated portions of the bolt, simultaneously forming the double-walled wings 46.

In accordance with the modification depicted in Fig. 25, the upper end of the tubular portion 130 is closed by the winged structure 132 extending across it. The bolt 134 20 is shown as having a splined head 136 received in the tubular portion 130 of the body, and as shown in Fig. 26, above the tubular portion, the body flares outwardly in substantially frusto-conical shape having an inner wall 138 and an outer wall 140. In this condition, the partially completed article is arranged in a fixture 126 supported by a table 124, similar to those corresponding parts depicted in Fig. 24, whereupon external dies 142 and 144 are brought together to collapse the frusto-conical portion of the body to form the double-walled wing structure 132 and secure the tubular portion 130 to the splined head 136 to prevent relative rotation of the parts. The product may be trimmed as provided in connection with previous examples, by means of suitable dies.

Whereas several modifications have been described for purposes of illustration, it will be recognized by those skilled in the art that the invention is applicable to many varieties of structures, and accordingly, the invention should not be limited to the examples selected beyond the scope of the appended claims.

- I claim:
1. A method of making winged fasteners from sheet metal stock comprising forming a flat blank into a body having a tubular substantially cylindrical portion and an oppositely directed tubular flaring wing-forming portion diverging therefrom, pressing opposed wall surfaces of said wing-forming portion into contact to produce wings and a continuation of said tubular portion, and pressing said substantially cylindrical tubular portion radially to secure screw threads therein.
  2. A method as set forth in claim 1 including notching said blank to define wings before said forming operation.
  3. A method as set forth in claim 1 including upsetting said tubular portion to define a terminal radial flange.
  4. A method of making winged fasteners from sheet metal stock comprising forming a flat blank into a body having a tubular thread-carrying portion and an oppositely directed flaring tubular wing-forming portion diverging therefrom, pressing opposed wall surfaces of said wing forming portion into contact to produce wings and a continuation of said tubular portion, providing a screw thread for said thread-carrying portion, and upsetting said tubular thread-carrying portion to produce a radially extending annular flange.
  5. A method as set forth in claim 4 including closing an end of said tubular portion remote from said thread-carrying portion.
  6. A method as set forth in claim 4 including closing an end of said tubular portion remote from said thread-carrying portion during said pressing operation.
  7. A method as set forth in claim 4 including internally threading said annular flange in spaced relationship to said tubular thread-carrying portion.
